Se-kit Yuen, 46 Hoi Yuen Road, 4th Floor, Kwun Tong,
Kowloon, Hong Kong

Filed Mar. 6, 1973, Ser. No. 338,623

Claims priority, application Great Britain Oct. 12, 1972

Term of patent 14 years

Int. Cl. D7—04

U.S. Cl. D7—157

FIG. 1

FIG. 2

FIG. 3

FIG. 5

FIG. 4

FIG. 1 is a side elevation of a combined mixer and dispenser for liquids showing my new design;

FIG. 2 is a rear elevation thereof;

FIG. 3 is a top plan view thereof;

FIG. 4 is a bottom plan view thereof;

FIG. 5 is a front elevation thereof.

I claim:

The ornamental design for a combined mixer and dispenser for liquids, substantially as shown and described.
